ATTORNEY

within the chamber is dissolved in the gasoline and the liquid gasoline takes the place of the air. At all times the gasoline in the compression chamber is under some pressure and it is never withdrawn. Even when the nozzle check valve 25 is opened, the pressure in the line leading from the pump to the nozzle is not sufficiently reduced to withdraw the gasoline from the compression chamber.

10 According to this invention, I have found that an expansion chamber 33 connected to the inlet or suction side of the pump and also to the outlet or pressure side of the pump will compensate for the thermal expansion of the gasoline trapped 15 between check valve 32 and nozzle check valve 25. The expansion chamber 33 is connected by a small conduit 34 to the suction side of the pump 16, as shown at 16a, and another conduit 35 is connected to the conduit 19 on the pressure side of the pump 20 16, as shown at 35a. It should be understood that the line 34 may be connected at any point between the check valve 32 and the intake of the rotor pump 16, but preferably at a point near the inlet side of the pump. The conduit 35 may be 25 connected at any point in the line between the outlet side of the pump 16 and the see-gage 23.

The expansion chamber 33 should be constructed to withstand considerable pressure and the chamber may be made of any design and should 30 be of at least one liter capacity, although compression chambers of $\frac{1}{2}$ liter capacity have been successfully used. A lug 36, or any other suitable means, is fastened to the chamber and is provided with holes to receive a U-shaped clamp 37 which 35 detachably secures the chamber to the framework 10. The expansion chamber may be positioned at any point along the frame member 10, for example it may be placed below the level of the pump 16 or it may be placed at the level of the 40 see-gage 23, or any intermediate point. The conduits 34 and 35, which connect the expansion chamber to the inlet and outlet side of the pump, may be of any suitable size, but preferably from $\frac{1}{8}$ to $\frac{1}{2}$ inch in diameter. Instead of having the 45 compression chamber made separate from the other mechanisms of the pump, the chamber may be made integral with the filter 14 or pump 16, but in either case the compression chamber must be connected to both the inlet and outlet sides of 50 the pump.

Figure 2 shows a cross sectional view of one embodiment of the expansion chamber. The lower part of the expansion chamber is provided with a bushing 38 threadedly secured to the compression chamber, and a pipe coupling 39 is attached to the lower part of the bushing for connecting the line 34 to the expansion chamber. The face of the bushing projects into the chamber and is provided with a ball-valve seat 40, the float 55 valve adapted to control the flow of liquid from the expansion chamber comprises a ball 41 with a cork float 42 attached thereto by the rod 43 and nut 43a. The float may be coated with a suitable gasoline insoluble composition, or it may be made of metal. A hook 44, or other suitable stopping means, is attached to the lower part of the ball-valve by the arm 45 and disposed in the enlarged portion of the bushing, thereby permitting the ball-valve 41 to be raised only a short distance 60 from its seat.

70 One side of the expansion chamber is provided with an internally threaded boss 46 which is adapted to receive the coupling 47 for the line 35 that leads to the pressure or exhaust side of the pump 16. The opening through the boss 75

leads to the interior of the chamber and terminates in a cap 48 which is provided with small outlets as shown at 49. Secured to the top of the cap is a bell-shaped hood 50, which extends around and in a spaced relation with the periphery of the cap and terminates beyond the openings in said cap.

80 By the use of the expansion chamber attached to both the inlet and outlet sides of the dispensing pump, the thermal expansion of the gasoline in the closed pipe system of the dispensing pump is compensated for to such an extent that it is very difficult to detect the slightest increase in pressure during the hot seasons. When the pump 16 is started, the gasoline is forced through the line 19 and to or through the nozzle 25, and a small proportion of gasoline is also forced into the chamber 33 through the line 35 until the pressure of the air or vapors therein exceed the pressure setting on the by-pass valve 31. Usually 85 the by-pass valve is set for about 10 to 15 pounds pressure per square inch. As the gasoline begins to collect in the expansion chamber 33, the float 42 raises the ball check valve 41 from its seat and permits some of the gasoline to flow out of the chamber and into the suction side of the pump. By this operation, a small amount of gasoline 90 is circulated through the expansion chamber and as a result of this circulation a supply of air is always present in the expansion 95 chamber. When the pump 16 is stopped, the valve 41 remains off its seat until the gasoline in the expansion chamber will no longer support the float 42. As long as the ball valve remains 100 open, the expansion chamber also serves as a 105 reservoir and will compensate for the gasoline that leaks back into supply tank 13 through the check valve 32. However, the float valve seats before all of the liquid flows from the expansion 110 chamber, thereby maintaining a portion of liquid 115 in the expansion chamber at all times.

If desired, I may use an expansion chamber that does not have a valved opening. In such cases, the flow pipe leading from the intake conduit 120 communicates with the bottom of the expansion chamber, and the small pipe leading from the outlet side of the pump communicates with the side or top of the expansion chamber. This type of construction is not as satisfactory as the construction where the small conduit from the suction line is provided with a valved opening in the 125 expansion chamber, because this modification does not assure the maintenance of a small amount of liquid in the expansion chamber.

As a further modification of my invention, the 130 boss 46 may be placed in the bottom of the expansion chamber adjacent the float valve 41, instead of being disposed on one side of the expansion chamber. Also instead of using the float valve 41 and 42 as herein described, I may use any 135 other suitable valve that opens when the pressure or level of gasoline within the expansion chamber exceeds a predetermined amount.

I have described my invention with reference 140 to a wet hose type, of pump, that is, the type of pump where the flow of liquid is controlled by a nozzle check valve on the end of the dispensing conduit, but it should be understood that I may use the compression chamber on the inlet and exit side of any type of pump or dispensing 145 means.

While my invention has been described with reference to a gasoline dispensing pump, it should be understood that other similar liquids may be dispensed from the pump. The scope of my in- 150

vention is to be determined by the following claims and not by the specific disclosure as hereinabove set forth.

I claim:

liquid from the tank, a suction line connecting the pump and the tank, a check valve in said line for preventing return flow of the liquid drawn by said means, a delivery conduit, a normally closed valve controlling the outlet of said delivery conduit, and an expansion chamber adapted to contain liquid and air under pressure connected to the suction side and the exhaust side of said pumping means whereby a small quantity of liquid can be circulated through said expansion chamber.

80
